UNITED STATES PATENT OFFICE

CHARLIE L. HAWES, OF ASHTABULA, OHIO

REDUCTION GEARING

Application filed December 1, 1927. Serial No. 236,897.

The present invention, as indicated, relates to reduction gearing and the objects of the invention are to provide such a mechanism in which a very high reduction may be obtained with small power loss and with relatively few parts, and in which all of the parts are enclosed in a relatively small housing. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a broken side elevation partly in section of one form of the present invention; Fig. 2 is an axial section of another form of the invention; Fig. 3 is a transverse section on the line 3—3 in Fig. 1; Fig. 4 is a transverse section on the line 4—4 in Fig. 2; Fig. 5 is a fragmentary section showing another modification; and Fig. 6 is a section taken on a plane indicated by the line 6—6, Fig. 5 with the shaft pinion removed.

Referring more particularly to Fig. 1, the reference numeral 1 indicates generally an electric motor having a shaft or spindle 2 and an end frame 3 provided with an annular laterally projecting skirt 4. A cover plate 5 is provided to form with said skirt an enclosed housing, and said cover plate is secured to said skirt by means of screws 6 or other equivalent fastening means.

Keyed to said shaft 2 and within the housing are two pinions 7 and 8, these being spaced apart on shaft 2 by a spacing ring 9. As illustrated, the pinion 7 is shown of larger diameter than the pinion 8, but it will be understood that in any given case the particular diameters and ratios will depend upon the particular speed requirements in hand. The pinions are held against possible movement longitudinally of the shaft by means of a nut 10 threaded onto a screw threaded portion 11 of said shaft 2. Stub shafts 12 are mounted in bores 13 in the end frame 3 and

are secured in position by means of nuts 14 bearing on the inner wall of said end frame and enlarged portions 15 bearing on the opposite face of said end frame. Idler pinions 16 are mounted to rotate on the enlarged portions 15 of the stub shafts 12 and, as is clearly shown in Fig. 1, said idler pinions mesh with opposite sides of the shaft pinion 7.

A disk 17 having a diameter substantially equal to the inside diameter of the housing is mounted for rotation in said housing and bears against the inner face of the cover plate 5. Said disk 17 is provided with a lateral projection 18 extending from its outer face and journaled in an aperture 19 in the cover plate 5. Beyond the cover plate 5 the extension 18 may be reduced, if necessary, as at 20, for the reception of a belt or pulley, gear or coupling, or other appliances for receiving power. The extension 18 is provided with a bore 21 in which is mounted a bushing 22, and the reduced end 23 of the shaft 2 is journaled in said bushing 22.

The disk 17 carries on its inner face at diametrically opposed points one or more hubs 24 on which are mounted pinions 25 meshing with the shaft pinion 8. An annular internal gear 26 is journaled in the housing, its external diameter being substantially equal to the internal diameter of the housing, and said gear is held against lateral movement between the inner wall of the housing and the disk 17. The gear 26 is provided with two toothed paths 27 and 28 for engagement with the idler pinions 16 and 25 respectively, the pitches and diameters of the various elements in any given case being determined by the particular speed requirements. A bearing 29, preferably of ball or roller type, is provided between the shaft 2 and the housing.

In the operation of the device, the motor 1 rotates the shaft 2 which in turn rotates the pinions 7 and 8. The pinion 7 rotates the idler pinions 16 which in turn transmit the power to the annular internal gear 26 through the teeth 27. Thus, if the shaft 2 is rotated in a clockwise direction as seen from the right of Fig. 1, the gear 26 is rotated in a counter-clockwise direction at a reduced rate of ro-

tation. Rotation of the gear 26 causes consequent rotation of the idler pinions 25, and since these are in mesh with pinion 8 which travels with the shaft 2, the hubs 24 and with them the disk 17 receive a motion in translation or creep around, as determined by the differential between the pinion 25 and the pinion 8. According to the particular diameters and speeds of the various elements, the extension-hub 20 may in such manner be rotated at a desired rate and in a desired direction.

In the construction illustrated in Fig. 2, the shaft 2' is journaled in a casing made up of end members 30 and 31 connected by means of bolts 32 or similar elements and which may be spaced from each other by a plate 33 and a large spacing ring 34. Pinions 7' and 8' are keyed to the shaft 2' and are spaced longitudinally of the shaft by means of a spacing ring 9'.

The plate 33 is rigidly held in the housing and is provided with apertures 13' on opposite sides of the shaft 2' for the reception of stub shafts 12' held in position by means of nuts 14' and enlarged portions 15' within the housing. The enlarged portions 15' carry one or more idler pinions 16' in mesh with the larger shaft pinion 7'.

A rotatable disk 17' is mounted in the housing and is provided with a cylindrical projection 18' extending from the outer face thereof and journaled in any suitable bearing, as a ball-bearing or a roller-bearing, or for example a bushing 35 mounted in the portion 36 of the end plate 31. The extension 18' may be formed with a cylindrical recess 37 for the reception of a bearing or a bushing 38 in which is journaled a reduced extension 39 of the shaft 2'.

The disk 17' carries one or more stub shafts 40 in apertures 41, said stub shafts being held in position by nuts 42 and enlarged portions 40'. Idler pinions 25' are carried on the enlarged portions 40' in mesh with the shaft pinion 8'. An annular internal gear 26' is journaled in the housing, the external diameter of said gear being substantially equal to the internal diameter of the spacing ring 34, and said gear 26' is held against lateral movement between the plate 33 and the disk 17'. The gear 26' is provided with two toothed paths 27' and 28' in mesh with the pinions 16' and 25' respectively.

The operation of the device disclosed in Fig. 2 is identical with that of the device disclosed in Fig. 1 except that power is applied to the shaft 2' by means of some external power source through a belt, a chain, or a train of gears or coupling.

In the form shown in Figs. 5 and 6, the motor shaft 2a mounted in any suitable bearing 29a carries a pinion 43 which is in mesh with pinions 44, 45, which in turn are mounted on stub shafts 46 held in the end frame 3a.

A disk 17a is journaled in a cover plate 5a by a gudgeon projection 18a. Peripherally, the disk member 17a carries an internal annular gear 47 which is in mesh with the pinions 44 and 45. With this construction, as the motor shaft with its pinion 43 rotates, the pinions 44, 45 are rotated, but these being mounted on fixed axes exert a turning movement on the ring gear 47 and thus to the projection or extension hub 18a which may carry any desired member to be rotated. The particular gear ratios in any instance will depend upon the drive rate required.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A power transmission unit comprising a housing, a shaft journaled in said housing, pinions of unequal pitch diameters fixed on said shaft, a pinion mounted in said housing for rotation about a fixed axis and meshing with one of said shaft pinions, a disk provided with a cylindrical projection from one face thereof, said projection being journaled in said housing and upon said shaft, a pinion carried by said disk in mesh with the other of said shaft pinions, said disk and housing pinions having unequal pitch diameters and an internal annular gear having its periphery journaled in the internal surface of said housing in mesh with said fixed pinion and with said disk pinion, said disk having its peripheral portion located between said housing and said annular gear and maintaining said annular gear in longitudinal position in said housing.

2. A power transmission unit comprising an electric motor having a stationary housing, a shaft journaled in said housing, a pair of pinions of unequal pitch diameters keyed to said shaft, a pinion mounted in said housing for rotation about a fixed axis and meshing with one of said shaft pinions, a disk provided with a cylindrical projection from one face thereof, said projection being journaled in said housing and surrounding said shaft, pinions carried by fixed hubs on said disk in mesh with opposite sides of the other of said shaft pinions, and an internal annular gear having its periphery journaled in the internal surface of said housing in mesh with said fixed pinion and with said disk pinions, and having its one peripheral side in sliding contact with said disk and its other peripheral side in sliding contact with said housing.

3. A power unit comprising the combination with an electric motor including a shaft and having a skirt projecting from one end frame thereof concentric with said shaft, of

a cover plate forming, with said skirt, a housing, a pair of pinions keyed to said shaft, a pair of pinions carried by said end frame and positioned in said housing in mesh with one of said shaft pinions, a disk mounted in said housing and provided with a cylindrical projection from one face thereof, said projection being journalled in said cover plate, said cover plate axially restraining said disk, a pair of pinions carried by said disk in mesh with the other of said shaft pinions, and an internal annular gear having its periphery journalled in the internal surface of said skirt and having two tracks, one meshing with said housing pinions and the other meshing with said disk pinions, said disk axially restraining said annular gear.

4. A power unit comprising the combination with an electric motor including a shaft and having an integral skirt projecting from one end frame thereof concentric with said shaft, of a cover plate forming, with said skirt, a housing, a pair of pinions of different diameters keyed to said shaft and spaced longitudinally thereof, a spacer ring on said shaft between said pinions, a pair of stub shafts in said end frame and projecting into said housing on opposite sides of said shaft, pinions mounted on said stub shafts in said housing and meshing with the larger of said shaft pinions, a disk in said housing and having a cylindrical projection extending from one face thereof, said projection being journalled in said cover plate, said projection being formed with a bore, a bushing in said bore, said motor shaft being journalled in said bushing, a pair of hubs projecting from the opposite face of said disk, pinions mounted on said hubs and meshing with the smaller of said shaft pinions, and an annular internal gear journalled in said housing and held against lateral movement therein between said end frame and said disk and meshing with said stub shaft pinions and with said hub pinions.

Signed by me this 28th day of November,
1927.

CHARLIE L. HAWES.
